(57) **CLAIM**

The ornamental design for modular cabinets, as shown and described.

DESCRIPTION

FIG. 1 is a front, right side, top perspective view of modular cabinets showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is front, right side, top perspective view of the modular cabinets shown in a separated state;

FIG. 10 is a front, right side, top perspective view of the middle one of the modular cabinets as illustrated within FIG. 9; and,

FIG. 11 is a front, right side, top perspective view of the two end ones of the modular cabinets as illustrated within FIG. 9 and shown as being connected together.

The broken lines depict portions of the claimed design for the modular cabinets which form no part of the claimed design.
